UNITED STATES PATENT OFFICE

2,315,179

PUMPING OF LIQUIDS

Samuel S. Allender, New York, N. Y., assignor to
 Universal Oil Products Company, Chicago, Ill.,
 a corporation of Delaware

Application December 18, 1939, Serial No. 309,755

1 Claim. (Cl. 103—224)

The invention relates more specifically to an improved method and means of absorbing shock and reducing the magnitude of pulsations in the discharge line of a reciprocating pump due to the intermittent nature of the flow of liquid from the pump cylinder or cylinders. It is adaptable to the pumping of all volatile liquids or liquids having constituents which are readily vaporized and is particularly advantageous in pumping inflammable liquids and those to which the presence of air may be detrimental.

It is, of course, common practice to provide an expansion chamber on the discharge line, manifold or outlet valve chamber of reciprocating pumps to assist in absorbing pulsations and minimize shock resulting from the intermittent nature of the pumping action. Heretofore, such devices have merely provided an entrapped body of air which is compressed and expands with variations in the pump discharge pressure and acts as a cushion. In the present invention this air cushion is replaced by a cushion comprising vaporized constituents of the liquid being pumped. This is accomplished by supplying sufficient heat to the upper portion of the expansion chamber to maintain a portion of the fluid in the expansion chamber in vaporous state.

Heating of the expansion chamber and vaporization therein may be accomplished, for example, by providing a closed coil within or a jacket or coil about the upper portion of the chamber and circulating a suitable heating medium therethrough. In case the pump is driven by steam or other hot expanding gas, a portion thereof may be passed through the coil or jacket to supply heat to the upper portion of the expansion chamber and maintain a vapor cushion therein. The heating medium in such cases may be bled from the inlet or exhaust line of the pumping cylinder, depending upon the temperature required to vaporize a portion of the liquid being pumped within the expansion chamber. With pumps driven by internal combustion engines, a portion of the hot exhaust gases may be employed as the heating medium. The invention also contemplates the use of a resistance coil or immersion type heating element supplied with electrical energy to accomplish vaporization in the upper portion of the expansion chamber, particularly when the pump is electrically driven and/or when other heating means are not readily available.

The use of a continuously maintained vapor cushion in place of an air cushion in the expansion chamber has numerous advantages, partic-

ularly as applied to specific pumping problems. In addition to eliminating the dangers which sometimes result from the presence of air when combustible or inflammable liquids are being pumped, the features of the invention obviate the possibility of ultimate practical elimination of the cushion in the expansion chamber when the pump is in continuous service over a prolonged period of time. For example, nearly all liquids will dissolve varying amounts of air and over a prolonged period of operation the air cushion in the pumping cylinder may be thus dissipated, whereas with the present invention, although vapors may also be dissolved from the cushion in the pumping cylinder and/or condensed by the liquid present, the continuous application of heat causes the evolution of additional vapor to replace that dissolved or condensed so that equilibrium conditions are established and a vapor cushion is continuously maintained, regardless of the length of time during which the pump is continuously operated.

The accompanying drawings diagrammatically illustrate several specific forms of apparatus, each embodying the features of the invention and in which the improved method of operation provided by the invention may be accomplished.

Fig. 1 illustrates a steam driven pump having an expansion chamber heated by steam supplied thereto from the inlet or from the exhaust line of the steam end of the pump.

Fig. 2 is an enlarged longitudinal elevation shown partially in cross-section, of the steam heated expansion chamber shown in Fig. 1.

Fig. 3 is a longitudinal elevation, shown partially in section, of a modified form of expansion chamber which may employ steam or other hot fluid as the heating medium.

Fig. 4 is an elevational view of an electrically driven reciprocating pump having an electrically heated expansion chamber.

Fig. 5 is an enlarged elevational view, shown partially in section of a portion of the expansion chamber shown in Fig. 4.

Fig. 6 is an elevational view, shown partially in section, of a portion of a modified form of electrically heated expansion chamber.

Referring to Fig. 1, the reciprocating type of steam driven pump here illustrated has a steam cylinder 10 and a liquid pumping cylinder 11 interconnected in the conventional manner, steam being supplied to the valve chest 12 through line 13 and exhausted therefrom through line 14.

The liquid to be pumped is supplied to the

valve chamber of the fluid end of the pump through suction line 15 and directed therefrom through discharge line 16. The expansion chamber 17 communicates with discharge line 16 and a closed coil 18 is provided in the upper portion of the expansion chamber. Steam may be supplied to coil 18 from the inlet steam line 13 through line 19 and valve 20 or exhaust steam from line 14 may be supplied to the coil through line 21, valve 22 and line 19. Steam and any condensate formed in coil 18 are discharged therefrom through line 23 and valve 24. Valves 20 and 22 are block valves and valve 24 is regulated to maintain the desired flow of steam through the coil.

Exhaust steam may be utilized in coil 18 when its temperature is sufficient to maintain a substantial portion of the liquid being pumped in vaporous state in expansion chamber 17 and when the back pressure in the exhaust steam line is sufficient to force steam through the coil at the required rate. In other instances, live steam from line 13 may be employed.

Referring now to Fig. 2, to facilitate the insertion of coil 18 in the upper portion of the expansion chamber and facilitate its removal for inspection and repair, whenever necessary, the upper head of the chamber is a flanged bonnet 25 removably bolted to the flanged substantially cylindrical lower portion of the chamber as indicated at 26. Packing glands 27 are provided in bonnet 25 through which the inlet and outlet ends 28 and 29, respectively, of coil 18 extend.

Referring now to Fig. 3, the expansion chamber here designated by the reference numeral 30 of conventional form, except that a jacket 31 is provided at its upper end and spaced from the walls 32 of the chamber. Steam or other hot fluid of sufficient temperature to maintain a substantial portion of the fluid within the expansion chamber in vaporous state is admitted to the space 33 between jacket 31 and the upper portion of walls 32 through line 34 and after transferring heat through walls 32 to the fluid within the chamber, the spent or partially spent heating medium is discharged from space 33 through line 35.

With a pump driven by an internal combustion engine, the arrangement may be substantially the same as illustrated in Fig. 1, except that an expansion chamber of the general type shown in Fig. 3 is preferably employed and only the combustion gas exhaust line, corresponding to line 14 of Fig. 1, is connected with the steam jacket of the expansion chamber through line 34, which replaces lines 21 and 19. No valve will ordinarily be required in this line but a regulating valve, preferably of the gate or butterfly type, may be employed in the outlet line 35 from space 33 in the same manner as valve 24 is employed in Fig. 1.

An expansion chamber of the general form shown in Fig. 3 may be substituted, in Fig. 1, for the type shown in Figs. 1 and 2 and is preferably employed when exhaust steam is utilized as the heating medium since it may be designed to offer less resistance to the flow of steam.

Referring now to Fig. 4, the reciprocating pump here illustrated is of conventional form except for the heating means provided in the upper portion of the expansion chamber 40. A motor 41, supplied with electrical energy

through lines 42, is connected through pinion 43 with gear 44 and pitman 45 connects gear 44 with piston rod 46.

The valve chamber 47 of the pump is mounted above the pumping cylinder 48, the inlet line for the fluid to be pumped communicating with the valve chamber on the opposite side of the pump from that here illustrated. The discharge line which communicates with the valve chamber is indicated at 49.

Expansion chamber 40, in the particular case here illustrated, is integral with bonnet 50 of the valve chamber and an immersion type electrical heating unit 51 is provided in the upper portion of chamber 40. Electrical energy is supplied to heater 51 through lines 52 from lines 42, which supply electrical energy to motor 41, and a suitable switch indicated at 53 is provided in one of the lines 52.

Fig. 5 illustrates how the immersion type heating element 51 may be inserted into the upper portion of chamber 40 through a threaded port 54 at the upper end of the chamber, the upper end of rod 51 being threaded to engage the threads 55 of the port and seal the chamber. Resistance wires 55 of heater 51 are electrically insulated from the metal outer walls of the latter, preferably by a heat conductive material such as for example magnesium oxide, porcelain or the like, not illustrated.

The expansion chamber 60 shown in Fig. 6 may be substituted for chamber 40 of Figs. 4 and 5 and is similar thereto except that instead of providing an internal or immersion type heating element, the heating element is disposed about the exterior surface of the upper walls of the chamber. The heating element of chamber 60 comprises resistance wires 61 encased in a substantially rigid body 62 of electrical insulating, heat conductive material such as magnesium oxide, for example. Resistance wires 61 form a coil which is connected at its opposite ends to terminals 63 to which conductor wires 64, form a suitable source of electrical energy, are also attached. The rigid molded shape 62 conforms to the contour of the upper portion of the walls of chamber 60 and is encased in suitable heat insulating material 65.

It will be understood, of course, that it is within the scope of the invention to employ an electrically heated expansion chamber with pumps driven by steam or other expanding hot gases and also that an expansion chamber heated by steam or other hot fluid may be employed on electrically driven pumps. Many specific forms of electrically heated or fluid heated expansion chambers, other than the specific forms illustrated, are, of course, also within the scope of the broader aspects of the invention.

I claim as my invention:

In combination, a fluid pump driven by an electrical power means, leads connecting said power means with a source of electricity, means for equalizing the pulsations of said pump comprising a chamber mounted in the discharge line of said pump, means for heating said chamber comprising a casing mounted on the outside of said chamber, heat conducting electrical insulating material within said casing, resistance elements in said casing mounted within said material, and means for connecting said resistance elements with said source of electricity.

SAMUEL S. ALLENDER.
